DESIGN FOR AN OIL BURNER

Burdell S. Williams, Dayton, Ohio

Application October 30, 1939, Serial No. 87,945

Term of patent 14 years

To all whom it may concern:

Be it known that I, Burdell S. Williams, a citizen of the United States, residing at Dayton, in the county of Montgomery and State of Ohio, have invented a new, original, and ornamental Design for Oil Burners, of which the following is a specification, reference being had to the accompanying drawing, forming part thereof.

Fig. 1 is a top plan view of an oil burner showing my new design;

Fig. 2 is a rear elevational view; and,

Fig. 3 is a side elevational view thereof.

The dominant features of my design reside in the portions shown in full lines.

I claim:

The ornamental design for an oil burner, as shown and described.

BURDELL S. WILLIAMS.
